G. A. BONELLI

SPIRAL WIRE FORMING DEVICE

Filed Oct. 31, 1921

Inventor:
George A. Bonelli:
by *Hazard & Miller*
Atty.

UNITED STATES PATENT OFFICE.

GEORGE A. BONELLI, OF KINGMAN, ARIZONA.

SPIRAL-WIRE-FORMING DEVICE.

Application filed October 31, 1921. Serial No. 511,613.

To all whom it may concern:

Be it known that I, GEORGE A. BONELLI, a citizen of the United States, residing at Kingman, in the county of Mohave and State 5 of Arizona, have invented new and useful Improvements in Spiral-Wire-Forming Devices, of which the following is a specification.

My invention relates to a wire coiling 10 device, the principal objects of my invention being to provide a relatively simple and practical device that may be advantageously and economically employed for the rapid coiling of wire that is utilized for 15 springs or for coiled reinforcing members for concrete construction, and particularly for concrete or cementitious pipe.

Further objects of my invention are to 20 provide a wire coiling machine that is of relatively simple structure capable of being easily and cheaply produced and which may be adjusted to form coils of different diameters and with the coils or convolutions disposed immediately adjacent to each other 25 or spaced apart, which latter arrangement is desirable in the production of certain forms of springs and reinforcing elements.

With the foregoing and other objects in 30 view, my invention consists in the features of construction and combination and arrangement of parts hereinafter more fully described and claimed, reference being had to the accompanying drawings, in which:

Figure 1 is an elevational view of a wire 35 coiling device of my improved construction;

Fig. 2 is a side elevational view of the wire coiling machine;

Fig. 3 is a detail perspective view showing 40 the forms for the production of cementitious pipe, with a reinforcing member arranged between said forms, which reinforcing member comprises an open coil of wire that is formed upon my improved machine;

Fig. 4 is a sectional view similar to Fig. 3 and showing the reinforcing member in the form of a closed coil of wire that is formed 45 by my improved machine.

Referring by numerals to the accompanying 50 drawings, which illustrate a practical embodiment of my invention, 10 designates the body of the machine, which body comprises a substantially rectangular block of

metal and which is provided on its lower end with a pair of laterally projecting ears 55 or lugs 11 that are adapted to receive the edge of a suitable support, for instance, a table, and to firmly secure the machine in position upon said support a clamping screw 12 is seated in the lower one of lugs 11 and 60 is adapted to engage and clamp the edge of the table against the upper one of said lugs.

The upper left hand corner of the block 10 is provided with a recess 13, thereby 65 forming at said corner a pair of spaced ears or lugs 14, and journaled therein is a short shaft 15 carrying on its forward end a roller 16 having a groove formed in its periphery, and on the opposite or rear end of said shaft 70 is fixed a pinion 17.

Journaled in the ears 14 immediately adjacent to shaft 15 and preferably in the same horizontal plane therewith is a shaft 18 on the forward end of which is secured 75 a grooved roller 19 that lies immediately adjacent to roller 16. Secured on the rear end of shaft 18 is a pinion 20 that meshes with the pinion 17 on the rear end of shaft 15. 80

Journaled on shaft 15 between the ears 14 is the lower portion of an upwardly projecting block 21, and journaled in the intermediate portion thereof is a horizontally disposed shaft 22 carrying on its forward end a grooved roller 23 that normally occupies a position adjacent to and above roller 16. Secured on the rear end of shaft 22 is a pinion 24 that meshes with pinion 17 on the rear end of shaft 15. 90

Pivots connected to a pin 25 that projects rearwardly from the upper portion of block 21 is the upper end of an arcuate rod 26, the same projecting laterally and downwardly and the end portion of said rod 95 passes through an aperture that is formed in the rear end of a bolt 27 which latter passes through the upper right hand corner of block 10. The forward end of bolt 27 or that portion which projects forwardly 100 of block 10 is threaded to receive a lock nut 28 and mounted upon said bolt 27 beneath said nut is the outer end of a plate 29, the inner end thereof being bent into an inclined plane as designated by 30, thereby providing 105 a spreading member which when moved up-

wardly so as to engage the coils of wire formed by the grooved rollers 16, 19 and 23 will spread or separate the convolutions thereof to form open coils. This arrangement is desirable in the production of certain forms of springs and reinforcing elements.

Journalized in the lower left hand portion of block 10 is a horizontally disposed shaft 31 on the rear end of which is fixed a gear wheel 32, and the teeth thereof mesh directly with the teeth of pinion 17. Secured to the rear face of this gear wheel 32 is the inner end of a crank handle 33.

15 In the operation of my improved wire coiling machine, the device is clamped to the edge of a support and the end of the section of wire to be coiled is inserted between the grooved rollers 16 and 23, as shown by dotted lines in Fig. 2, and the end of said wire is extended downwardly between the grooved rollers 16 and 19.

20 Crank handle 33 is now engaged and actuated to rotate shaft 31, and the rotary motion thereof will be transmitted through gear wheel 32 to pinion 17 and from the latter to pinions 20 and 24, and, consequently rotary motion will be imparted to the grooved wheels 19 and 23 that are associated with grooved wheel 16.

25 The wire in passing between the grooved wheels 16, 19 and 23 will be formed into a coil as shown in Fig. 1, which coil as it is produced gradually moves outwardly or away from the forming wheels. Under normal conditions, or with the spreading member 30 shifted into position so that it is out of engagement with the coil of wire, as it is being formed, the convolutions of said coil 30 will lie immediately adjacent to each other, thereby producing a closed or close coil. In the event that it is desired to produce an open coil or a coil wherein the convolutions are spaced apart, the inclined end 30 of member 29 is raised until it engages between the coils of wire as they pass from between the grooved rollers 16 and 19 and as a result said coils will be spread apart. Obviously, the vertical adjustment of the spreader 30 will regulate the space between the convolutions of the coiled portion of the wire.

35 To regulate the diameter of the convolutions formed by the grooved rollers while the machine is in operation, block 21 carrying grooved roller 23 is swung upon shaft 15 so as to adjust grooved roller 23 toward or away from roller 19, which adjustment is attained by moving the free end of arcuate rod 26 through the opening in the end of bolt 27, and after the parts have been properly adjusted nut 28 is tightened to lock the arcuate rod in its adjusted position. As grooved roller 23 is adjusted toward the roller 19, the convolutions of the coiled wire will be rel-

atively large in diameter, and as said roller 23 is adjusted away from roller 19, the diameter of the convolutions will correspondingly decrease.

40 In some instances it may be found desirable to mount my improved machine on a suitable frame or supporting standard that may rest upon or be secured to the floor, and, further, shaft 31 may be equipped with a belt receiving pulley or sprocket wheel 75 and driven from any suitable source of power.

45 Thus it will be seen that I have provided a relatively simple and practical machine for coiling wire that is to be used for a variety of purposes, for instance, in the production of bed and furniture springs and for coiled wire spacing members and reinforcements for cementitious work, and particularly tubular members of concrete or cementitious material.

50 By utilizing wire that has a certain degree of resiliency, coil springs of various lengths and diameters may be readily produced, and said springs may be utilized for compression or retractile purposes.

55 In Figs. 3 and 4, I have shown pairs of concentrically arranged cylinders or forms that are utilized in the construction of cementitious pipe, and with coils of wire arranged in the spaces between said forms to serve as spacers and reinforcing members.

60 Various changes in the size, form and construction of the parts of my improved wire coiling machine may be made and substituted for those herein shown and described without departing from the spirit of my invention, the scope of which is set forth in the appended claims.

65 I claim as my invention:

70 1. A wire coiling device comprising a body, a member, a shaft extending through the member and body to rotatably support the former on the latter, a roller fixed to the shaft, a second shaft journalized in the member, a roller fixed to the second shaft, a third shaft journalized in the body, a roller carried by the third shaft, means for actuating all of said shafts, and a curved arm adjustably connected to the body for holding the member in any desired position.

75 2. A wire coiling device, comprising a body having spaced ears, a member provided with an extension arranged between the ears, a shaft extending through the ears and extension and rotatably mounted therein, a roller fixed to the shaft, a second shaft journalized in the member, a roller fixed to the second shaft, a third shaft journalized in the ears, a roller carried by the third shaft, means for actuating all of said shafts, and means for holding the member in any desired position.

80 3. A wire coiling device, comprising a body having spaced ears, a member provided

with an extension arranged between the ears, a shaft extending through the ears and extension and rotatably mounted therein, a roller fixed to the shaft, a second shaft journalled in the member, a roller fixed to the second shaft, a third shaft journalled in the ears, a roller carried by the third shaft, means for actuating all of said shafts, and an arm adjustably mounted on the body and connected to said member for holding the latter in any adjusted position. 10

In testimony whereof I have signed my name to this specification.

GEO. A. BONELLI.
